LYMAN F. WHITNEY, OF BOSTON, MASSACHUSETTS, ASSIGNOR TO KALMUS COM-
STOCK & WESCOTT, INC., OF BOSTON, MASSACHUSETTS, A CORPORATION OF
MASSACHUSETTS.

HEADLIGHT SCREEN.

Application filed October 25, 1920. Serial No. 419,194.

To all whom it may concern:

Be it known that I, LYMAN F. WHITNEY, a citizen of the United States, and resident of Boston, in the county of Suffolk and 5 State of Massachusetts, have invented new and useful Improvements in Headlight Screens, of which the following is a specification.

My invention relates to a multiple reflecting translucent screen of a type particularly adapted for use with automobile headlights or lights of that character used for other and similar purposes.

Automobile headlights of types now in 15 general use comprise a parabolic reflector with a source of light such as an incandescent bulb placed in the focus of the reflector. Such a light will theoretically deliver a beam composed of parallel rays. In practice it does not deliver such a beam but delivers a cone-shaped beam comprising an inner smaller cone consisting of the reflected light and an outer cone consisting of direct rays from the light source, the outer cone 25 being limited in size only by the opening in the front of the reflector. The reflector rays are cone-shaped rather than parallel due to the fact that the reflector is not a perfect parabola and the source of light is 30 not a theoretical point, and therefore even if a portion of the filament is located at the exact focus, other portions extend outside that point.

In the practical use of such lamps for 35 automobile headlights the lighting effect desired is illumination of the roadway to as great a distance as is commensurate with the strength of the light, without the emission of blinding rays extending above the 40 plane of the lamp itself. This latter requirement is caused by the fact that intense rays extending upward will blind drivers of approaching vehicles or pedestrians and be a source of danger and of accidents. 45 Moreover, the use of headlights without illumination so restricted is prohibited by law in many jurisdictions.

The light to be most desired therefore is one which presents a sharply defined upper boundary with intense light immediately adjacent the upper boundary since it is this light which will be directed substantially parallel to the road and which will be useful for illuminating purposes, at the extreme 55 range of the light.

In so far as I am aware the only effective method for accomplishing these desired results is by means of the utilization of the principle of total reflection as described in the patent of Daniel F. Comstock No. 1,377,- 60 184, granted May 10, 1921.

The utilization of the principle of total reflection permits of a sharp line of cleavage between the rays directed inside the critical angle of the lens or screen used and those 65 impinging thereon outside of the critical angle. These two classes of rays may be readily separated and either class may be utilized for illuminating purposes, giving a beam sharply defined on one side. 70

However, the prior utilizations of this principle made use of but a single total reflection, which method has certain undesirable results. The phenomena of total reflection are such that, while all rays incident 75 at angles greater than the critical angle are reflected, not all rays incident at angles less than the critical angle are transmitted, but a certain portion of these latter rays are also reflected. Therefore if the screen utilizes 80 the reflected rays, it projects all of the rays outside the critical angle, but it also projects some rays which are inside the angle and consequently the resultant beam has some upwardly extending rays. On the other 85 hand, if the screen utilizes only the transmitted portion of those rays incident at less than the critical angle, it does not secure all the rays inside the angle since portions of such rays are reflected. Since the percentage 90 of reflected rays is greater adjacent the critical angle and it is the rays at this point which should form the brilliant upper portion adjacent the boundary of the beam, the loss of efficiency in the light is quite marked. 95

It is an object of my invention to provide a new and improved translucent screen especially adapted for use with automobile headlights or the like, which screen will effectively limit the resultant beam of light 100 within a predetermined sharply defined boundary, which will give the maximum efficiency within that boundary, and which will have a substantially uniform action throughout its surface upon light rays impinging thereon. It is an object to provide a screen adapted to selectively divide the light rays and to transmit without sensible diminution all rays having certain directional characteristics and to obstruct 105 110

or to render non-blinding substantially all rays having other directional characteristics. It is also an object to provide a screen which will produce a beam of light having a sharply defined boundary upon one side and having substantially its maximum illuminative effect adjacent this boundary. It is another object to provide a screen which will permit the utilization of the greatest possible proportion of the light energy of the light source without producing a light having any intense rays so directed as to be blinding in their effect. Other and further objects will appear as the description proceeds.

I have illustrated certain preferred embodiments of my invention together with diagrams illustrative of the principle of the invention with accompanying drawings in which,

Fig. 1 shows one form of my screen as seen from the rear, the rim being partly broken away;

Fig. 2 is a vertical section on line 2—2 of Fig. 1;

Fig. 3 is a horizontal section on line 3—3 of Fig. 1;

Fig. 4 is a detail view showing the action of the screen illustrated in Figs. 1 to 3; Fig. 5 is a view similar to Fig. 1 showing another embodiment of the invention;

Fig. 6 is a vertical section on line 6—6 of Fig. 5;

Fig. 7 is a horizontal section on line 7—7 of Fig. 5;

Fig. 8 is a detail view showing the action of the screen illustrated in Figs. 5 to 7;

Fig. 9 is a vertical longitudinal section through a headlight having a double-reflection screen;

Fig. 10 is a detail view showing the action of the screen illustrated in Fig. 9; and

Fig. 11 is a diagram illustrative of the principle of my invention.

In the form of my invention shown in Figs. 1 to 4, the screen consists of a face plate 7, having the reduced circumferential portion 8, and having its outer face formed with the vertically extending cylindrics 9 which meet to form the ridges 10. This plate is held in frame 11 by the flanges 12 which are bent down against the reduced circumferential portion 8 of the plate. The opposite edge of the frame carries the flange 13 adapted to be utilized in connecting the frame to a lamp or the like. Fitting against the plate 7 in the frame 11 are the trapezoidal prisms 14 which are similar in cross-section but which vary in length as shown in Fig. 1 in order to fill the circular frame. The rear faces of the prisms 14 slope upwardly and rearwardly, the purpose of which will be discussed hereafter. The spaces 15 formed at the end of the prisms may be filled with cement or any

suitable filler in order to maintain the prisms positively in fixed relation. Thin sheets of translucent paper or similar material 30 may be placed between the adjacent faces of the several prisms or there may be placed between these surfaces any material, or the surfaces may be coated with a film of any material, adapted to diffuse, absorb or otherwise obstruct any light passing through the surfaces, the surfaces themselves, regardless of the external element of treatment, serving to totally reflect all light impinging thereon at angles greater than the critical angle and a small portion of the light within that angle.

The screen shown in Figs. 5 to 8 is similar to that shown in Figs. 1 to 4 in that it comprises a rim 11', a front glass 7', and transverse prisms 14' separated by light obstructive layers of paper or aluminum or other suitable material, the prisms being mounted in the rim by suitable material as shown at 16'. However, instead of the prisms being inclined on their rearward surfaces as shown in Figs. 3 and 4, their rearward surfaces are all disposed in the same vertical plane and the forward faces are inclined. Moreover, instead of the cylindrical surfaces being formed on the front of the glass 7' they are formed on the front of the prisms. Obviously the cylindrical or light spreading surfaces might be placed on the rear face of either the prisms or front glass.

In Fig. 9 I have shown a headlight of the usual type comprising the shell 16, the reflector 17, electric bulb 19 with filament 20, the shell having a flange 18 coacting with the flange 21 on the frame 22, which latter contains the plates 23 and 24 carrying the oppositely faced, interfitting prisms 25 and 26 respectively. The plates are so placed as to provide the spaces 27 between the oblique faces of the prisms and these spaces may be treated in the same manner as was described relative to the adjacent faces of the prisms shown in Figs. 1 to 8. The outer face of the plate 23 is provided with vertical concave cylindrics 28 similar to those provided on the outer plate 7 of the other forms of the device.

My invention, in each of its forms just described in some detail, is designed to utilize the reflected light, that is the light totally reflected by the oblique prismatic surfaces of the screen. As has been stated, all light is reflected which impinges upon the reflecting surfaces at an angle greater than the critical angle, which angle in glass such as that normally used for such screens, is approximately $41^{\circ} 8'$, the index of refraction being approximately 1.52. On the other hand, some of the light impinging at less than the critical angle is also reflected and the relative amount is substantially as

shown in Fig. 11. In this figure the ordinates represent percentages of the total light which is reflected and the abscissæ represent angles of incidence in degrees, 5 the zero in the scale being the critical angle. Those degrees on the left of the scale indicate angles greater than the critical angle, and as the curves show all such light is reflected. The degrees to the right of zero 10 indicate angles less than the critical angle and they are therefore marked as negative angles. The curve A represents the light reflected upon a single reflection, the curve B upon a double reflection and the curve C 15 upon a quadruple reflection. The meaning of these curves and the effective result of the facts they indicate may perhaps be made more clear by considering a concrete example.

20 Assuming that a single-reflection critical-angle reflector (as disclosed e. g. in the aforesaid Comstock patent) is placed at such an angle that all light impinging thereon at the critical angle is reflected horizontally and all rays impinging thereon at angles greater than the critical angle are reflected at corresponding angles below the horizontal, it is clear from curve A of Fig. 11, that although there will be a pronounced 25 drop in the intensity of the light at the horizontal plane, nevertheless more than 30% of the light reaching the critical angle reflector at 1° less than the critical angle will be reflected and will be inclined upwardly 1° . Similarly more than 20% of the reflected light will be directed upwardly 2 $^\circ$, and even at 5° within the critical angle 10% of the light will be reflected. It will readily be understood that in the case of 30 a high-powered headlight even 10% of its light energy will produce a blinding light and light directed upward through 5° and starting from the level of the usual automobile headlight will extend upward sufficiently to blind a pedestrian or driver quite close to the light.

Considering this curve A from the opposite view point and taking it in connection with those types of critical angle reflecting 35 screens which utilizes the transmitted or non-reflected light, the area below the curve represents the light lost, and since the most intense and useful light is that directed nearest the horizontal it is apparent that such screens leave something to be desired from the point of efficiency.

But if, instead of using a single critical angle reflector a plurality of such reflectors are arranged in succession, as illustrated in 40 the drawings for example, the percentage of light which passes through the screen within the critical angle is greatly reduced, as shown in Fig. 11 where the curve B shows the amount of such light in a multiple-reflection and curve C in a quadruple

reflect 45 such as illustrated in Figs. 1 to 8. Taking the aforesaid example of light incident at 1° within the critical angle it appears from Fig. 11 that instead of 30% of such light passing through as in a single 50 reflecting screen only about 10% passes through in a double reflecting screen and practically none passes through in a quadruple reflecting screen. It therefore appears that a multiple reflecting screen is 55 far more effective in eliminating upward glare; at the same time the intensity of the beam at and near its upper boundary, and consequently its effectiveness to illuminate the distant roadway, is extraordinarily effective.

The action of the screen shown in Fig. 9 is illustrated in the diagram of Fig. 10. The ray *a* entering along the horizontal impinges upon the total reflecting oblique 60 surface of the prism 26 at substantially the critical angle and is therefore reflected. It passes down through the lower horizontal face of the prism 26 and the upper horizontal face of the adjacent prism 25 of the 65 other series at angles less than the critical angle and is transmitted. It then impinges upon the oblique surface of the prism 25 at an angle greater than the critical angle and is reflected, the several angles of the prisms 70 being proportioned so that it passes forward substantially horizontally. Obviously all rays reaching the original reflecting surface at an angle greater than the ray discussed, 75 will be acted upon in the same manner.

However, rays such as indicated by *b* of Fig. 10 which impinge upon the original reflecting surface 26^a at angles less than the critical angle will be largely transmitted 80 through said surface and only in small part reflected by this surface as indicated by the curves of Fig. 11. Taking *b* as being 5° less than the critical angle, at the first surface 85 substantially 90% will be transmitted and 90% reflected. Of this 10% which is reflected, when it reaches the second reflecting surface 26^b, 90% of it, or 9% of the original light, is transmitted leaving 1% of the original intensity to be reflected forward and upward at 5° above the horizontal, as shown 95 by the curve B of Fig. 6. Except in very strong headlights, 1% of the intensity will not be sufficient to be blinding. Considering now the 90% of the original ray *b* which 100 was transmitted through the first reflecting surface, this light is obstructed by one of the methods disclosed, and is preferably diffused by a non-transparent film, such as a sheet of 105 paper interposed between the two prisms, the thickness or light transmissive quality of the film or sheet of paper depending upon the intensity of the light with which it is to be used. The 9% of the original light which 110 is transmitted through the second reflecting surface is diffused by the film between that 115 120 125 130

surface and the adjacent one. If even a sharper cut-off is desired than that given by a double reflection the form of my device shown in Figs. 1 to 8 which gives four reflections may be used.

The action of the screen shown in Figs. 1 to 3 is illustrated in Fig. 4. Light entering from the rear (the left in Fig. 4) is reflected as indicated by ray C if it strikes the critical-angle reflecting surface outside the critical angle; otherwise most of it passes through the critical-angle surface (as shown by curve A in Fig. 11) and is either absorbed or diffused or otherwise obstructed depending upon the material 30 placed between the prisms. If the critical-angle reflecting surfaces be so inclined that the light entering the prisms horizontally is incident at substantially the critical angle, e. g. just inside the critical angle, then substantially no light is projected from the headlight above the horizontal. By inclining the rear faces of the prisms as shown, the light is bent down upon entering the screen, whereby each ray leaves the screen in a lower direction than it enters. In this way rays which are upwardly inclined before entering the screen may be transmitted and projected in or below a horizontal direction, thereby increasing the efficiency of the screen without decreasing its remarkable non-glare qualities. The light issuing from the screen is spread by the cylindrical surfaces 9 on the cover glass 7.

35 The operation of the embodiment shown in Figs. 5 to 8 is similar to that of the first embodiment, but the light is bent downward upon leaving the prisms instead of upon entering and the spreading surface is located on the forward face of the prism instead of on the front face of the cover glass. Thus both the front and the rear faces of the screen are flat and smooth.

In a double-reflecting lens such as shown 45 in Fig. 9, the following arrangement (hereinafter referred to as the principal example) has been found satisfactory. The critical-angle reflecting surfaces are set at such angle to the horizontal that the horizontal rays are 50 incident to the reflecting surfaces 1° within the critical angle, thus permitting approximately 11% of such rays to be projected (see curve B in Fig. 6). Rays inclined above the horizontal 1° are incident to the reflecting surfaces 2° within the critical angle and only approximately 6% of such rays are projected. And rays inclined downwardly only 1° are substantially 100% projected inasmuch as they are incident at the critical 60 angle.

If the horizontal rays above referred to are the parallel rays of the light beam, i. e., the rays parallel to the axis of the reflector, which are the most effective rays, it is obvious that these rays are largely obstructed,

thereby greatly lowering the efficiency of the headlight for distant illumination. However, the present invention is adapted to produce the sharp cut-off at the horizontal (or at any other desired elevation) 70 and at the same time utilize these most effective rays to much greater advantage. This may be accomplished in several ways of which the following are examples: first, by bending all the projected rays downwardly, say 1° before reflection (Figs. 1 to 4); secondly, by bending the reflected rays downward after reflection (Figs. 5 to 8) in which case the critical angle surfaces are inclined at a lesser angle to the horizontal 75 than in the principal example, say 1° less; thirdly, by placing the critical angle surfaces as in the principal example and then tipping the paraboloidal reflector so that its axis is inclined 1° below the horizontal, 80 without tipping the screen; and fourthly, by tipping the entire headlight including both the paraboloidal reflector and the screen downwardly say 1° and at the same time 85 inclining the critical angle reflecting surfaces at a 1° lesser angle to the axis of the headlight than in the principal example; etc. In each of these four cases the line or 90 plane or boundary of the top of the beam would remain unchanged in position, e. g. assuming the upper boundary of the projected beam horizontal in the principal example, it would be horizontal in each of the four cases mentioned.

When employing light-diffusing layers 100 between, the prisms, as for example strips of paper, the upwardly directed light which is transmitted through the critical angle reflecting surfaces is very useful as diffused light to illuminate the sides of the roadway 105 and to make the headlights visible at points above their level, but is not of sufficient intensity to be blinding.

Although I have described my invention 110 as utilized in connection with an automobile headlight, it is obviously of much broader application. It may be used in any situation where a light having a sharply defined boundary is desired, as for example in flood lighting of signs or buildings and in other 115 situations demanding light of similar characteristics.

I claim:

1. A screen for headlights comprising 120 transparent media having total-reflecting surfaces for transmitting light therethrough by successive reflection from said surfaces, and light-obstructing means behind said surfaces for substantially preventing direct transmission of light passing through said 125 surfaces.

2. A translucent screen for headlights or the like having total-reflecting surfaces arranged to reflect a plurality of times and transmit without substantial diminution 130

light incident to said surfaces at angles greater than the critical angle, the screen having means to diffuse light incident to said surfaces at angles less than the critical angle.

3. A translucent screen for headlights or the like having juxtaposed total-reflecting

surfaces set at oblique angles to the plane of the screen and having means placed between said juxtaposed surfaces adapted to 10 obstruct light passing through said surfaces.

Signed by me at Boston, Massachusetts, this 15th day of October 1920.

LYMAN F. WHITNEY.
